UNITED STATES PATENT OFFICE.

MARTIN J. PALMER, OF CHICAGO, ILLINOIS.

POCKETBOOK PROTECTOR.

1,423,539.

Specification of Letters Patent. Patented July 25, 1922.

Application filed September 3, 1921. Serial No. 498,510.

To all whom it may concern:

Be it known that I, MARTIN J. PALMER, a subject of the King of Sweden, and a resident of Chicago, county of Cook, and State 5 of Illinois, have invented certain new and useful Improvements in a Pocketbook Protector, of which the following is a specification.

This invention relates, generally, to improvements in protectors or guards, but particularly, to a protector or protecting attachment for various types of pocket books, such as, bill-folds or bill-books, card and cigar cases, memoranda-books, and the like, 10 which are usually carried in the breast pockets of coats or the hip-pockets of trousers, and it consists in certain peculiarities of the construction, novel arrangement and combination of the various parts there- 15 of, as will be hereinafter more fully set forth and specifically claimed.

The principal object of the invention is to provide a protector or guard for pocket books and the like, which shall be simple 20 and inexpensive in construction, strong, durable and efficient in operation, with its parts so made and arranged, that it can be readily attached to a pocket book without in any way marring or disfiguring the same, and 25 when attached, will be so disposed thereon that the book may be easily placed in a pocket or removed therefrom without interference by the protector, but when desired, the protector can be caused to engage the 30 pocket in such a manner as to prevent the loss or accidental removal of the book from the pocket, or its removal therefrom by a pick-pocket or thief, yet, so that the book owner can instantly disengage it and remove 35 the book.

Another object is to provide automatic means for releasing the pocket engaging member of the protector from its normal position.

40 Other objects and advantages of the invention will be disclosed in the following description and explanation.

In the accompanying drawing, which 45 serves to illustrate an embodiment of the invention—

Fig. 1 is a side view of a pocket bill book shortened for the convenience of illustration and illustrating by continuous lines my 50 protector applied thereto, with its parts in their normal positions but showing by dotted lines about the position the pocket en-

gaging arm of the protector will assume when released from its normal position.

Fig. 2 is a view in elevation looking towards the edge of the book to which the 60 protector is secured, showing the parts in their normal positions.

Fig. 3 is a fragmental view of a garment with a pocket therein and illustrating a book equipped with any attachment located in 65 the pocket and about the position the pocket engaging arm will assume after being released from its normal position and in engagement with the pocket to prevent the removal of the book.

70 Fig. 4 is a greatly enlarged longitudinal sectional view of a portion of that part of a pocket book to which the attachment is secured, showing the attachment mounted on the book and the parts thereof in their normal positions.

75 Corresponding numerals of reference refer to like parts throughout the different views of the drawing.

The reference numeral 7 designates a 80 pocket book which may be of any suitable size, form, material, and of the ordinary or well known construction. Longitudinally mounted on and secured to one of the edges of the book 7 is a securing plate which is 85 designated as a whole by the numeral 8, and comprises an elongated piece of sheet metal having its end portions outwardly curved in cross-section to correspond with the curvature of the edge of the book on which it 90 is mounted. These end pieces of the plate are secured to the book by means of rivets 9 or in any other suitable or well known way. Between the end portions of the securing plate 8 said plate is provided with a 95 pair of spaced lugs 10 which are located longitudinally on the plate 8 as will be readily understood by reference to Figs. 1 and 2 of the drawing. One of the curved end portions of the securing plate 8, that is, 100 the upper one thereof, is provided with an outwardly extended and downwardly disposed hook 11, which hook is by preference integral with the securing plate.

105 Mounted at its lower end between the lugs 10 and secured thereto by means of a pivot pin 12 is a pocket engaging arm or member 13 which is provided at its upper or free end with a knob 14 or blunt end. This arm is preferably hollow or tubular in form and 110 has its portion adjacent the book 7 provided with a longitudinally extended slot 15 for

the reception of the free end of the hook 11 which is adapted to enter said slot at the upper end thereof. At a suitable distance below the upper end of the slot 15 that surface of the arm 13 adjacent the book 7 is provided with a transversely disposed shoulder 16 to act as a stop for a sleeve 17 which is slidably mounted on the arm 13 for engagement with the free end of the hook 11 as shown in Figs. 1 and 4 of the drawing, so as to hold the arm 13 in its normal or folded position. Located within the lower portion of the cavity of the arm 13 and coiled around the pivot 12 of said arm is a spring 18 one end of which extends through the slot 15 of the arm and rests against the securing plate 8 while the other end of said spring rests against the wall of the arm 13 at a point above its pivot. By this arrangement it is obvious that by placing the arm in the position shown by continuous lines in Figs. 1 and 4 of the drawing, where it may be held by sliding the sleeve 17 upwardly on the arm until it engages the hook 11, that the spring 18 will be under tension. When the parts are in the position just above described, it is manifest that the pocket book carrying the attachment can be readily inserted in a pocket or removed therefrom without interference by the attachment. In order to guard against the accidental removal of the book, or against its removal by a pick-pocket or thief, it is only necessary to press the upper end of the arm 13 towards the book, which will permit the sleeve 17 to be disengaged from the hook 11 and descend until it rests on the shoulder or stop 16 of the arm, when it is evident that the spring 18 will cause the arm 13 to assume about the position shown in Figs. 1 and 3 of the drawing, thereby causing the upper end of the arm 13 to engage the lining or wall 19 of the pocket in about the manner shown in Fig. 3 of the drawing. When the arm is thus positioned, it is quite obvious that the pocket book cannot be removed from the pocket without restoring the arm 13 to its normal position, or at least without disengaging the upper end of the arm 13 from the cloth of the pocket.

In Fig. 3 the reference numeral 20 designates a portion of the garment on which the pocket 19 is formed, which pocket may be of the ordinary or well known construction.

To disengage the arm 13 from the pocket 19, it is obvious that by inserting the hand into the pocket at the open end of the latter, the sleeve 17 may be reached by one of the fingers of said hand, when, by tilting the arm 13 from its inclined position towards

the pocket book, it is apparent that the sleeve can be slid upwardly on the arm and thus caused to engage the hook 11 and thus hold the arm in its normal position, when of course the book can be removed from the pocket without interference by the attachment.

Having thus fully described my invention, what I claim as new and desire to secure by Letters Patent is—

1. A protector for pocket books and the like comprising an elongated plate adapted to be secured to a book longitudinally thereon, said plate having at one of its ends a hook, an arm pivoted at one of its ends to the said plate below the hook thereon and having in its surface adjacent the hook a longitudinally disposed slot for the reception of said hook, and a sleeve slidably mounted on the arm and adapted for engagement with the hook.

2. A protector for pocket books and the like comprising an elongated plate adapted to be secured to a book longitudinally thereon, said plate having at one of its ends an outwardly disposed hook, a spring actuated arm pivoted at one of its ends to the said plate below the hook thereon and having in its surface adjacent the hook a longitudinally disposed slot for the reception of said hook, said arm also having a stop member located at a distance from the upper end of said slot, and a sleeve slidably mounted on the arm above said stop member and adapted for engagement with the hook.

3. A protector for pocket-books and the like, consisting of an arm pivotally mounted at one of its ends on the book near one end thereof and adapted for movement in a plane with the body of the book, a hook mounted on the book above the pivot of said arm and in the path of the travel of said arm, and means carried by the arm for detachably engaging said hook.

4. A protector for pocket-books and the like, consisting of a spring-actuated arm pivotally mounted at one of its ends on the book near one end thereof and adapted for movement in a plane with the body of the book, a hook mounted on the book above the pivot of said arm and in the path of the travel thereof, said arm having in its surface adjacent the hook a longitudinally disposed slot for the reception of the hook and also having a stop member located at a distance from the upper end of said slot, and a sleeve slidably mounted on the arm above said stop member and adapted for engagement with the hook.

MARTIN J. PALMER.
